UNITED STATES PATENT OFFICE.

SAMUEL L. BOGGS, OF IVANHOE, VIRGINIA.

APPARATUS FOR SEPARATING ORES FROM GANGUE.

1,324,791.

Specification of Letters Patent. Patented Dec. 16, 1919.

Application filed July 12, 1918. Serial No. 244,560.

To all whom it may concern:

Be it known that I, SAMUEL L. BOGGS, a resident of Ivanhoe, in the State of Virginia, have invented a new and useful Improvement 5 in Apparatus for Separating Ores from Gangue, of which the following is a specification.

This invention relates to apparatus for separating ores from gangue, etc. More 10 broadly it relates to flotation apparatus for effecting separating of granular materials of different specific gravity, which may be ores and gangue, or merely loose mixtures of different materials, from any source.

15 The objects of the invention are to provide an apparatus into which the mixture to be separated may be constantly fed, at a uniform rate, there exposed to continuous agitation in a suitable flotation compound, and 20 the solid material graded into two classes of different specific gravity, and continuously withdrawn from the apparatus.

25 Other objects and advantages of the apparatus will be apparent to those familiar with the art, and will in part appear throughout the following specification.

Referring to the drawings, Figure 1 is a 30 plan view of the apparatus; Fig. 2 is a vertical section on the line 2—2 of Fig. 1; Fig. 3 is a vertical section on the line 3—3 of Fig. 1; and Fig. 4 is a longitudinal vertical section on the line 4—4 of Fig. 1.

The apparatus comprises a main tank having sides 1 and 2, ends 3 and 4, a bottom 5, 35 a supplementary operating bottom 6, a longitudinal partition 7 seated upon the operating bottom 6, and extending only a part of the length of the tank, as shown in Fig. 1. Near the end 3 of the main tank is a trans- 40 verse partition, composed of sliding vertical doors 8 and 9, mounted in grooved supports 10 and 11 fixed on the interior of side walls 1 and 2, respectively, and an intermediate supporting post 12. This post 12 also has a 45 notched guide-way in which a door 13, parallel to the side walls of the main tank is mounted. The other side of the door is en- gaged by a guide-way 14, mounted on the end of longitudinal vertical partition 7. On 50 the inside of walls 1 and 2 are fixed vertical baffle plates 15 and 16 respectively. Similar and oppositely disposed baffle plates 17 are attached to the middle partition 7, the details of these baffles being clearly shown in 55 Figs. 1 and 2.

Shafts 18 and 19 are mounted in suitable

bearings in the end walls 3 and 4, and extend longitudinally throughout the tank, midway between the dividing partitions and the side walls thereof. These shafts are driven by a 60 motor M, which is suitably connected by chains 20 and 21 to said shafts. A clutch 22, operated by a hand lever 23, is provided for applying and disconnecting the power from the motor to drive the shafts. It will 65 be understood that any suitable driving means may be used, and that such means and its connection are not a part of my invention.

Mounted on shafts 18 and 19 are a series 70 of paddles 24 and 25, respectively. These paddles are set at an angle of about 37° to a plane perpendicular to the axis of the shaft, and the paddles 24 on shaft 18 are set so that as that shaft is rotated counter-clockwise, considered from the end 3 of the tank, liquid in the compartment A between the partition 7 and the wall 1 will be driven from the end 3 toward the end 4 thereof. The paddles 25 on the shaft 19 are inclined 80 in an opposite direction, so that as that shaft is likewise rotated counter-clockwise, liquid in the compartment B between the wall 2 and the middle partition will be driven from the end 4 toward the end 3. This flow is in- 85 dicated by arrows on the drawing.

It will be seen that three of the paddles are set comparatively close together at the driven end of the shaft 18, and two paddles close together at the opposite end of that 90 shaft, similarly and at the corresponding end of shaft 19. The purpose of this arrangement will be set forth more fully below.

A chain 26 connected to one of the shafts above referred to, drives, by suitable connections, such as gears 27 and 28, and chains 29 and 30, two shafts 31 and 32, upon which are mounted screw conveyers 33 and 34, shown in detail in Figs. 3 and 4. These conveyers are of standard type and detailed 100 description is unnecessary. They form only an element of my combination, and are not claimed otherwise as a part of my invention.

These conveyers are inclosed by circular 105 casings 35 and 36, respectively, which extend from the side wall 1 of the tank to a point above the normal water level in the apparatus. The conveyers are inclined at an angle, as shown in Fig. 3. At the outer 110 end the casing 35 has a discharge spout 37, on its under side. The inner end of the con-

veyer 34 extends into a compartment C formed by transverse dividing walls 39 and 40, extending from the bottom of the tank and from side to side thereof, up to, and 5 supporting the false bottom 6, above referred to. The partition, or false bottom 6, has a transverse opening 41 therethrough, as shown in Figs. 1 and 4. The gate 9, above referred to, is divided horizontally at 10 about its middle point, as shown in Figs. 3 and 4, the lower half being marked 9^a.

A horizontal dividing partition 42 is provided, and it is adapted to seat on the supporting brackets 43, as shown in Figs. 1, 15 3, and 4, forming an upper compartment E and a lower compartment D.

A chute, or hopper 44, is provided to feed the material to be separated to the apparatus.

20 The operation is as follows:

The tank is filled with water to the level indicated by the dotted line in Figs. 2, 3, and 4. This covers the paddle wheels and the coöperating baffle plates and leaves several inches of water above the tops of these 25 elements. The upper part of door 9 is removed, leaving only the lower part 9^a in position. The door 8 is placed in position, shutting off the compartment D in which 30 the conveyer 33 is situated, from the remainder of the tank, except for the connection therebetween caused by the removal of the door 9. Normally the false bottom 42 is not used, so that D and E form a single 35 compartment.

Granular divided material, such as ore and gangue or other mixtures of finely divided materials of different specific gravities, is fed into the apparatus from the 40 hopper 44. A suitable element such as oil, wood sulfite liquor, etc., is mixed with the water to cause a froth to be formed thereon. The paddle wheels are driven at a rapid rate, causing a violent agitation of the 45 liquid mixture, resulting in a thick froth on top, violent swirling and moving currents of water about the paddle wheels, and a more quiet condition thereof on the surface, just under the froth. The heavier particles 50 of the mixture will tend to drop below the paddle wheels and coöperating baffle plates, and to settle into the quieter water at the bottom of the tank. The lighter particles in the mixture will be constantly picked up 55 from this bottom recess, caught in the violent currents surrounding the paddle wheels, and will tend to be thrown out of the most active currents into the comparatively smoother portions on the surface of the 60 water beneath the froth. In this position they will be gradually picked up, held and carried on by the froth on top of the solution. Therefore, a separation will take 65 place, the heavier particles being gathered at the bottom of the tank, and the lighter

particles in the froth at the top. The inclination of the two series of paddles will cause the whole contents of the tank to flow slowly around in the direction indicated by the arrows. At the end of the 70 partition 7 the mixture will be driven across to the other side of the tank and then driven in the opposite direction by shaft 19 and its paddle 25. During all of this progress around the tank the separation of particles 75 of different specific gravities as above set forth will be carried on and completed.

The size of the tank, the number, inclination and speed of the paddles will be so chosen and adjusted, with respect to the 80 mixture to be separated, that by the time it has been carried from a point beneath the supply hopper to the last paddle on shaft 19, the separation will be complete. Consequently, the heavy particles on the bottom 85 will settle through the port 41 into the compartment 38, and be carried therefrom by the screw conveyer 34, and discharged into any suitable receptacle. The lighter particles, held in the froth on the top of the 90 tank, will pass over the partition 9^a, and into the compartment E, where they will gradually settle to the bottom of compartment D and be carried off by screw conveyer 33 and discharged through spout 37 95 to a suitable receptacle.

In certain cases it may be desirable to place the false bottom 42 in position on the supports 43, as indicated by dotted line in Fig. 4, separating compartments D and E, 100 and to simply gather the froth in the top compartment E, without allowing any material to settle to the bottom D. This, however, is a modification of the process, and like various other modifications, it may be 105 employed according to the particular circumstances.

Also, the gate 13 may be opened, to permit a continuous travel of the liquid around the tank, without any passage into the top 110 of compartment 45, simply drawing off the heavy particles by port 41.

A pipe 46 for supply water to the apparatus, and another pipe 47 for drawing it off are provided, and may be connected at 115 any suitable places.

It will be understood that suitable bearings, and mechanical attachments requisite for the most efficient operation of the various shafts, doors, power connections, etc., 120 will be provided, and that the drawings herewith are largely diagrammatic in character, and not intended to limit the construction of the actual apparatus in so far as actual details are concerned. It is intended 125 merely to illustrate the general principles, and the essential claimed features of construction and operation in the present case.

I claim:

1. Apparatus for separating mixtures of 130

- different specific gravity, comprising a tank having a central longitudinal dividing partition provided with a gap at one end, two horizontal shafts located at opposite sides 5 of said partition, paddles on said shafts adapted to agitate a mixture of water and material to be separated and to cause it to flow continuously around the end of the partition, means to drive said shafts, means to 10 supply material to the tank on one side of the partition and at the end opposite the gap in the partition, and means to draw off the lighter material from the top and the heavier 15 material from the bottom at the end of the tank opposite the gap in the partition, and on the opposite side of the partition from that where the material is introduced into the tank.
2. Apparatus for separating mixtures of 20 different specific gravities, comprising a tank, two horizontal shafts therethrough, means to drive the shafts, oppositely disposed paddles on the shafts, a dividing partition in the tank between the shafts, said 25 partition having a gap at each end, a gate inclosing the gap at one end of the partition, and a draw-off opening in the bottom of the tank on one side of said gate.
3. Apparatus for separating solid materials in granular form of different specific gravities, comprising a tank adapted to contain a liquid, shafts extending throughout the tank, paddles on said shafts adapted 30
- to cause the liquid to flow from end to end of the shaft, a vertical partition in the tank 35 between the shafts, an opening through said partition, baffles on the sides of the tank and on the said partition between said paddles, an opening in the bottom of the tank at the end of the cycle, a chamber beneath said 40 opening, an endless conveyer leading into said chamber and having its other end raised to a point above the water level of the tank, an overflow compartment connected to the tank, an endless conveyer leading 45 into the bottom of the overflow compartment and having its other end raised above the water line of the main tank, and means to drive the paddle shafts and conveyers.
4. Apparatus for separating materials of 50 different specific gravities, comprising a tank, horizontal driven shafts extending therethrough with oppositely disposed paddles thereon, a longitudinal partition between the shafts with a gap at each end, a 55 transverse partition across the shafts, gates in said transverse partition, a gate connecting the transverse partition to the longitudinal partition, and draw-off openings in the bottom of the tank, substantially as described.

In testimony whereof I have hereunto set my hand.

SAMUEL L. BOGGS.
